(57) **CLAIM**

The ornamental design for an exterior vehicular mirror housing and assembly, as shown and described.

DESCRIPTION

FIG. 1 is a perspective view of an exterior vehicular mirror housing showing our new design;

FIG. 2 is a first side elevational view thereof;

FIG. 3 is a second side elevational view as seen from the side opposite that of FIG. 2;

FIG. 4 is a first end elevational view thereof;

FIG. 5 is a second end elevational view as seen from the side opposite that of FIG. 4;

FIG. 6 is a rear view thereof;

FIG. 7 is a front view thereof, showing the interior of the housing;

FIG. 8 is a perspective view of a second embodiment hereof showing a exterior vehicular mirror assembly having the housing hereof with a pair of mirrors mounted thereto with a partial mounting shaft shown in phantom;

FIG. 9 is a rear view of FIG. 8;

FIG. 10 is a first side view of FIG. 8;

FIG. 11 is a second side view of FIG. 8, as seen from the side opposite that of FIG. 10;

FIG. 12 is a first end elevational view of FIG. 8; and,

FIG. 13 is a second end view of FIG. 8 as seen from the side opposite that of FIG. 12.
